UNITED STATES PATENT OFFICE.

HERBERT D. COOK, OF OMAHA, NEBRASKA.

MUSIC-LEAF TURNER.

Application filed March 9, 1923. Serial No. 623,936.

To all whom it may concern:

Be it known that I, HERBERT D. COOK, a citizen of the United States, residing at Omaha, in the county of Douglas and State of Nebraska, have invented certain new and useful Improvements in a Music-Leaf Turner, of which the following is a specification.

This invention relates to a device for turning music sheets, and has been designed for use particularly in connection with a piano, but can also be used in connection with music stands for the playing of other musical instruments.

One of the objects of this invention is to provide a device of the character indicated, which will securely hold a piece of sheet music in an operative position on the front of a piano, and which will automatically turn the leaves of the music as the operator presses a key carried by the device while playing one of the regular keys of the piano.

A further object of the invention is to provide a device of the character indicated, whereby the leaves can be automatically returned to their original position for replaying of the piece, as is very desirable in the use of a student learning to play the piano.

A still further object of my invention is to provide a music leaf turner of the above indicated character, which can be adjusted to fit the music leaf support that usually accompanies and forms a part of a piano.

And a still further object of my invention is to provide a music leaf turning device of the character indicated, which is not only ornamental in design and forms an attractive part of the piano, but one that is simple in construction and operation, durable, efficient for the purpose intended, and one that can be manufactured and placed on sale at a low cost.

These and like objects of the invention will be better understood as the description follows and as is specifically pointed out in the appended claims.

Referring to the accompanying drawings which form a part of this specification and

which clearly illustrate the construction and operation of my improved music leaf turning device,

Figure 1 is a front view of a music leaf turner constructed in accordance with my invention.

Figure 2 is a side elevation of same.

Figure 3 is a front view of my improved music leaf turner with the cover removed to better show the operation of same.

Figure 4 is a top plan view.

Figure 5 is a section taken on line 5--5 of Figure 3, and

Figure 6 is a section taken on line 6--6 of Figure 3.

Referring to the accompanying drawings in detail, like characters will be used to designate like parts in the different views.

In the drawings, the numeral 1 indicates as a whole my improved music leaf turning device, which comprises a back rest 2, a front plate 3, and a bottom connecting plate 4, also a top connecting plate 5. The bottom connecting plate 4 is pivotally connected to the back 2 as at 6, the purpose 75 of which will be better understood as the description follows.

Mounted in the top plate 5 intermediate the ends of same is a bolt 7 that extends downwardly a short distance within the hollow space formed by the back rest 2 and front plate 3. A pair of curved arms 8 and 9 are loosely mounted on the bolt 7 beneath the top 5, said arms 8 and 9 extending outwardly through a recess formed in the upper edge of the front plate 3. Each of the arms 8 and 9 is provided with a clamp 10 and a rest 11 for each sheet of music. The rests or supports 11 can be of any shape desired. For the purpose of showing my invention, I have made same approximately L-shape.

The lower edge of the front plate 3 is bent at right angles to form a ledge 12 on which the sheet music rests and clips 13 are employed for holding the sheet music or book as the case may be firmly against the face of the front plate by engaging the binding of same.

Positioned within the space formed by 100

the front and rear walls are three vertical operating rods 14, 15, and 16. The said rods 14, 15, and 16 are adapted to lay against the back wall 2 and are held in such position by means of a cross brace 17. The lower edges of the members 14, 15, and 16 are bent at right angles to provide keys 18. Each of the members 14, 15, and 16 is formed with a struck out portion adjacent the upper end as at 19, and a leaf spring as designated by the numeral 20 is fastened to the back rest 2 on its front face, and the end of each leaf spring engages the struck out portion 19 so as to hold the members 14, 15, and 16 in an upwardly extended position.

A series of sliding arms as indicated by the numerals 21, 22, and 23 are horizontally supported beneath the top 5, in brackets 24.

20 A series of L-shaped levers 25 are pivotally mounted on the back rest as at 26. The sliding rods 21, 22, and 23 are connected to one end of the pivoted levers 25 by means of a link 27. The other end of each of the levers 25 is connected to the upper end of members 14, 15, and 16 by means of a pivoted extension arm 28.

Assuming that the device is in an assembled position and that a piece of sheet music is supported on the front of the device, and that the operator of the piano wishes to turn over the first sheet, pressure is applied to the key formed on the lower end of the vertical sliding rod 14. As the member 14 moves downwardly against the tension of the spring 20, the member 25 swings on the pivot 26 causing the horizontal rod 21 to slide in the brackets 24 to the left of the holder, during which movement a recess 30 in the rod 21 is disengaged from the pin 31, thus causing the rod 21 to move upwardly so that the lug 29 formed integral therewith and extending at right angles thereto engages the curved arm 8, thus causing same to swing on the pivot 7 turning the clamp 10 and support 11 to the left of the music stand.

When desiring to turn the second sheet, pressure is applied to the key 18 of the vertical sliding rod 15, which acts in a similar manner on one of the links 25 to move the horizontal sliding rod 22 to the left, during which operation a similar lug 29^a engages the arm 9, bringing same along with the sheet music to the left of the stand. To permit the arm 9 to pass the lug 29 the recess 30 in the rod 21 engages the pin 31, so that the lug 29 of the bar 21 lies below the arm 9, as clearly illustrated in Figure 3 of the drawings.

Should both of the rests 11 be to the right of the stand, and it is desired to turn both to the left, pressure is applied on the key 18 causing the lug 29^a of the sliding rod 22

to move both of the arms 8 and 9 and the rests 11 along with the sheet of music to the left of the stand.

In order to provide means for permitting the return of the music to its original position, the horizontally sliding member 23 is employed, which is pivotally connected to the vertical sliding member 16, through the pivoted lever 25, link 27, and arm 28. When pressure is applied to the key 18 of the member 16, the rod 23 moves to the right of the casing permitting the lug 32 to engage the arms 8 and 9 moving same to their original position.

In order to provide means whereby the music leaf turner may be adjusted for engaging piano racks of various shapes and angles, the device is provided with connecting rods 33 and 34 on each side thereof, said connecting rods being adjustably secured together by means of a bolt and wing nut 35, so that the angle of the bottom connecting plate 4 may be varied with relation to the leaf turner proper.

In view of the foregoing description of my invention taken in connection with the accompanying drawing, it is thought that any further explanation as to the construction, operation, and objects of my invention is unnecessary.

While I have shown and described the preferred form of my invention, I realize that various minor changes may be resorted to, without departing from the spirit and scope of the invention as claimed, and therefore, I do not wish to limit myself to the exact details of construction shown, nor to the combination and arrangement of parts.

What I claim as new and desire to secure by Letters Patent is:

1. In a music leaf turner, comprising front and rear walls, a pair of leaf supporting arms pivotally supported between said walls, a manually operated rod engaging one of said leaf supporting arms for turning the same on its pivot, and a second manually operated rod engaging and turning both of said leaf supporting arms together and in the same direction as moved by said first mentioned manually operated rod.

2. In a music leaf turner, comprising front and rear walls, a pair of leaf supporting arms pivotally supported between said walls, a manually operated rod engaging one of said leaf supporting arms for turning the same on its pivot, a second manually operated rod engaging and turning both of said leaf supporting arms together in the same direction, and means arranged upon said first mentioned manually operated rod for permitting the same to be out of the path of the leaf supporting arms when said arms are turned.

3. A music leaf turner comprising front and rear plates, a lower plate pivoted to the rear plate, a pair of rods slidably connected together one being attached to the lower plate while the other is attached to the rear plate, means for locking said rods against sliding movement to hold the lower plate in adjusted position to fit various music racks on pianos, and a series of music leaf supporting arms pivotally connected between said front and rear plates. **10**

In testimony whereof, I have affixed my signature in the presence of two witnesses.

HERBERT D. COOK.
